FIBROUS SOUND PRODUCING MEANS AND
METHOD OF PRODUCING THE SAME

Jesse B. Hawley, Geneva, Ill.

Application July 27, 1931, Serial No. 553,296

19 Claims. (Cl. 92—57)

The present invention relates to fibrous sound producing means and the method of producing the same.

Among the objects of the invention is to provide a novel sound producing member composed of conjoined strata of different kinds of fibrous materials, such as soft and hard fibres, the material being preferably accreted and integrated to form an unitary integral member or unit. The member may be of the diaphragmatic type having a vibratile portion, such as a cone shaped part, and a supporting portion, such as a border or marginal part adapted to be secured to a frame or similar supporting means.

The supporting portion is designed to be flexible, pliable, and supple to afford unimpeded freedom of movement of the vibratile part when vibrated, while the vibratile portion is sufficiently stiff or rigid to maintain its shape when actuated to propagate or generate sound. The strata of the supporting or border portion are predominantly of soft fibrous material, such as textile fibres, as wool, cotton, linen, and the like so as to give the border or supporting portion pliability and suppleness.

The remainder of the border portion may be of harder or tougher fibrous material, such as wood pulp, paper pulp, and the like, so as to give the border portion durability or toughness, yet not affecting the pliability and suppleness of that part.

The vibratile portion is designed to be sufficiently rigid or stiff to sustain the load of propagating or generating sound or sound waves, without distortion, and without strains, the strata of this portion being predominantly of the harder or tougher fibres, such as wood pulp, paper pulp, and the like, the remainder of the strata being of softer fibres so as to give to the vibratile portion some resiliency and to reduce or eliminate parasitic resonance and the like, without affecting the stiffness of the vibratile portion as a whole.

Another object of the invention is to provide a novel process for producing the above mentioned article. The various strata or layers of laminae are alternately deposited, accreted and integrated upon a porous former, blanking means being used to blank off a portion of the former or previously deposited fibrous material, when depositing other fibrous material on the exposed part of the former or previously deposited fibrous material.

Other objects, advantages, capabilities, process steps, and structural features are comprehended

by the invention as will later appear, and as are inherently possessed thereby.

Referring to the drawings:

Fig. 1 is a fragmentary sectional view of a porous former and a blanking-off means on a part of a previously deposited stratum of hard fibrous material, and also showing a deposit of a stratum of soft fibrous material;

Fig. 2 is a similar view showing the blanking-off of the stratum of soft fibrous material and the further deposit of hard fibrous material on the previously deposited stratum thereof;

Fig. 3 is a similar view showing a completed integrated unitary member before it is stripped from the porous former;

Fig. 4 is a similar view showing the blanking-off of a central portion of the porous former and the depositing of a thin border stratum of hard fibrous material;

Fig. 5 is a similar view showing the blanking-off of the border stratum shown deposited in Fig. 4, and the depositing of a thick stratum of hard fibrous material and a thin stratum of soft fibrous material on the central portion of the former;

Fig. 6 is a similar view showing the blanking-off of the central strata of hard and soft fibrous materials shown deposited in Fig. 5, and the depositing of a thick border stratum of soft fibrous material and a thin border stratum of hard fibrous material;

Fig. 7 is a similar view showing the blanking-off of thick and thin border strata shown deposited in Fig. 6, and the depositing of a thick central stratum of hard fibrous material;

Fig. 8 is a similar view showing the blanking-off of a border portion of the porous former, and the depositing of a thin stratum of soft fibrous material on the exposed portion of the porous former;

Fig. 9 is a similar view showing the blanking-off of the deposit shown in Fig. 8, and the depositing of a thick stratum of soft fibrous material on the exposed border portion of the former, and also a deposit of a thin stratum of hard fibrous material upon said thick stratum of soft fibrous material;

Fig. 10 is a similar view showing the blanking-off of the border strata, and the depositing of a thick stratum of hard fibrous material, and a thin stratum of soft fibrous material; and,

Fig. 11 is a similar view showing the blanking-off of the central strata, and the depositing of a thick stratum of soft fibrous material.

Referring now more in detail to the drawings, the invention is practiced in connection with a

porous former comprising a plate 1 having a central conic portion 2, a marginal or border portion 3, and an intermediate rolled or undulated portion 4. At the edge, this plate has a flange 5 adapted to rest upon a table (not shown) capable of being lowered into a fibrous bath for submerging or immersing the former, and of being raised out of the bath after deposit of fibrous material on the former from the bath. Any suitable means may be used to effect such immersion into and withdrawal from a bath.

To the table may be connected a suitable suction duct whereby suction or a partial vacuum may be effected in a chamber 6 defined by the table, flange 5, and plate 1.

The plate 1 has a large number of apertures or holes 7 for the passage of the fluidal vehicle or medium, such as water, of the bath. The upper surface of the plate 1 is preferably formed 20 with grooves 8 which give into the drain holes 7.

Upon the ridges 9 of the plate 1 may rest a thin plate 10 having an innumerable number of fine holes or pores 11. Upon this plate 10 may rest a reticulated or foraminous member 12, although this member may be omitted if desired and the plate 10 be used to perform the function of member 12. The use of the member 12 sometimes facilitates the stripping of the wet fibrous blank, although the stripping of such a blank 30 from the plate 10 is practical, when the member 12 is omitted.

When it is desired to make a diaphragmatic sound producing member with the vibratile or conic portion entirely of hard fibrous material, such as wood or paper pulp, and the supporting or border portion mainly of soft fibrous material, such as textile fibres, as wool and the like, and partly of hard or tough fibrous material, as wood or paper pulp, the process used is illustrated in 40 Figs. 1, 2 and 3 of the drawings.

The former is first submerged in a pulp bath, and with the suction effective in the chamber 6, the water of the bath is drawn through the interstices of the member 12, the holes 11 of plate 10, 45 grooves 8 and holes 7 of plate 1 and thence to the suction duct. This effects a deposit, accretion and integration of pulp fibres into a thin stratum 13 over the surface of the porous member 12.

With the suction being still effective, the 50 former and table are raised out of the bath, and then a stopper plate or blanking-off member 14 having a conic portion 15 and a curved or curled border portion 16 shaped to conform with a part of the undulated or intermediate portion 4 of the plate, is placed upon the conic or vibratile portion 17 and a part 18 of the juncture or intermediate portion 19 of the pulp blank 13. The border portion 20 of this blank, as also the remainder 55 21 of the juncture 19, are left exposed.

The former is now immersed in a fibrous bath 60 of soft fibres, such as wool, cotton, or the like, so that a thick stratum 22 of soft fibrous material is deposited, accreted and integrated upon and with the exposed border portion 19 and curved 65 part 21 of the blank, thus forming a border stratum portion 23 and a curved juncture stratum part 24. The hard and soft fibres knit together and are infused and integrated so that there is an unitary integral mass composed of different 70 strata of fibrous material with no demarcation or cleavage. The former is then raised out of this bath. See Fig. 1.

The blanking member 14 is then removed, and another blanking member 25 comprising a border 75 blanking off portion 26 and a curved or curled

juncture blanking-off portion 27, and of annular form, is placed upon the stratum 25 to blank-off the border and juncture stratum portions 26 and 27. See Fig. 2.

The device is then submerged in the pulp bath 80 whereupon a thick stratum 28 comprising conic stratum portion 29 and juncture stratum part 30, is deposited, accreted upon, and integrated and united with the stratum 17 and the inner edge portion 31 of the stratum 22 of the border portion of the blank. See Fig. 2.

The blanking-off member 25 may then be removed, and the device again submerged in the pulp bath to deposit a thin stratum 32 to the full extent of the blank, this stratum comprising 90 a conic stratum portion 33, border stratum portion 34, and juncture stratum portion 35. The stratum 32 is deposited and accreted upon, and is integrated, infused and knitted with the conjoint strata 28 and 22, so as to form an unitary integral 95 fibrous blank, as clearly shown in Fig. 3.

The various strata are so blended together that there is a continuity of materials without demarcation, yet one portion, such as the conic or vibratile portion, is mainly of pulp fibres, and another portion, such as the border of supporting portion, is predominantly of soft or textile fibres, such as wool, cotton, flax, etc., the thin strata of pulp fibres in this portion giving the border portion durability and resilience without detracting from 105 the pliability and suppleness of this border portion.

The blank, thus produced, may be stripped from the mold or former, as by air pressure acting through the former to blow off the blank or 110 by suction above the blank and former to lift off the blank. The blank may then be compressed, if desired, dried, and treated with suitable materials such as latex for proofing the diaphragm against moisture and other climatic conditions, 115 and also other treating substances, as lacquer, and the like for adding stiffness to the conic portion, or other characteristics or properties as desired.

In use the diaphragm is supported by way of 120 the border portion which may be held between clamping means or the like, and the apical part of the conic portion is suitably connected to an electrical actuator or driver, or carries a voice coil operatively located in an electrodynamic gap. 125 The conic portion vibrates to produce sound, and part of the border portion and the juncture between the border portion and the conic portion flexes pliably to permit free movement of the vibratile conic portion of the diaphragm.

The form above disclosed comprises a conic vibratile portion wholly of pulp fibres, and the border or supporting portion mainly of soft fibres with laminæ of harder fibres, as at the surfaces thereof, but the blank may be made with any 130 number of strata of hard and soft fibres with varying degrees of thickness in the different portions of the diaphragmatic member.

In Figs. 4, 5, 6 and 7 is shown the mode of producing such a member whereby the vibratile portion predominates in pulp fibres with a thin stratum, as a core, of soft fibres, while the border or supporting portion predominates in soft fibres with thin strata of hard fibres.

In this case, a blanking-off plate 36 is first 145 placed on the conic part of the former. Then the device is submerged into a pulp bath to deposit a thin stratum 37 of pulp fibres on the exposed or border portion of the former. See Fig. 4.

Then the device is raised, the blanking mem- 150

ber 36 removed, and a blanking member 38 placed over the deposited stratum 37. The member 38 has a curled part 39 which is disposed in tapered space relation over the undulated juncture 40 of the former, so as to provide a beveled space 41 between the parts 39 and 40.

The device is again submerged in the pulp bath to deposit a thick stratum 42 on the former, and also a beveled splicing portion 43 in the space 41, 10 the inner edge of the border stratum 37 and the outer edge of the portion 43 knitting, integrating, and uniting to form a continuous integral stratum. See Fig. 5.

The device is then raised out of the pulp bath, 15 and is then submerged into another bath of soft fibrous material for the depositing of a thin stratum 44 on the exposed conic portion of the stratum 42 as clearly shown in Fig. 5. The stratum 44 accretes upon and integrates with the stratum 42 to form an unitary integral mass of materials. 20

After raising the device from the bath, the blanking-off member is removed and another blanking-off member 45 is placed upon the conic portion of the blank, as on the stratum 44. The 25 member has a curled border 46 which is disposed in tapered spaced relation over the stratum portion 43 so as to provide a beveled splicing space 47 between the part 46 and the stratum portion 43. See Fig. 6.

30 The device is then submerged in a bath of soft fibrous material and a thick stratum 48 is deposited and accreted upon, and integrated and united with the stratum 37 and stratum portion 43 to form an integral united mass of materials, 35 the soft fibres also accreting in the space 47 and forming a beveled splicing portion 49 which is also integrated and united with the pulp portion 43 as also with the edge portion of the stratum 44. See Fig. 6.

40 The device is then raised from the bath of soft fibrous material, and then submerged in a bath of harder fibrous material, such as pulp, and a thin stratum 50 of pulp is deposited accreted upon and integrated and infused with the stratum 48. See Fig. 6.

45 Then, the device, is raised out of the bath, the blanking-off member 45 removed, and the blanking-off member 38^a may then be placed upon the stratum 50, the curled part 39^a being spaced above 50 the stratum portion 49 to form a beveled or splicing space 51.

The device is then submerged in a pulp bath whereupon a thick stratum 52 of pulp is deposited and accreted upon and integrated and infused 55 with the stratum 44 and stratum portion 49, the fibrous material entering into the space 51 to accrete thereon and to integrate with the tapered stratum part 49 and also to integrate and unite with the inner edge portion of stratum 50. See 60 Fig. 7. The device may then be raised out of the bath and the blanking-off member 38 removed. In this way all the strata and portions thereof are united integrally together to form an unitary integral blank or unit of different materials with varying degrees of hard and soft fibres. 65 The blank may then be removed and finished as above mentioned in connection with the articles shown in Figs. 1, 2 and 3.

If desired, the strata may be arranged 70 conversely to that shown in Figs. 4, 5, 6 and 7, as shown in Figs. 8, 9, 10 and 11.

In this case a blanking-off member 51 having a curved portion 52 is first placed upon the border and juncture portions of the former, and then 75 the device is submerged into a bath of soft fibrous

material to deposit and accrete upon the exposed conic portion of the former, a thin stratum 53 of soft fibrous material. See Fig. 8.

After raising the device out of the bath and removing the blanking-off member 51, another blanking-off member 54 having a curled portion 55, is placed upon the stratum 53 with the part 55 in tapered spaced relation with the juncture portion 40 of the former so as to form a beveled space 56 between parts 55 and 40.

The device is then submerged into a bath of soft fibrous material whereupon a thick stratum 57 with a beveled splicing stratum portion 58 is deposited and accreted upon the exposed parts of the former, and integrated, united and infused with the outer edge portion of the stratum 53. See Fig. 9.

The device is then raised from the bath and then submerged into a bath of hard fibrous material, such as pulp, to form a thin stratum 59 which is deposited and accreted upon and integrated, infused and united with the exposed portion of stratum 57. See Fig. 9.

95 After raising the device from this bath, the blanking-off member 54 is removed, and another blanking-off member 60 having a curled portion 61, is then placed upon the stratum 59 with the curled part in tapered spaced relation above the splicing stratum portion 58 to form a beveled space 62 between part 61 and stratum portion 68. 105

The device is then submerged into the pulp bath, and a thick stratum 63 of pulp is deposited and accreted upon the exposed stratum 53 and in the space 62 to form a tapered stratum portion 64, and also is integrated, united and 110 infused with the stratum 53 and stratum portion 58, and also with the inner edge portion of the stratum 59. See Fig. 10.

The device may then be submerged into a bath of soft fibrous material to form a thin stratum 65 115 deposited and accreted upon and integrated, united and infused with stratum 63.

After raising the device from this bath, the blanking-off member 60 is removed and blanking-off member 54^a is placed upon stratum 65, 120 with the curled part 55^a in tapered spaced relation over the beveled splicing stratum portion 64, to form a beveled splicing space 66 between part 55^a and stratum portion 64.

The device is then submerged in a bath of soft 125 fibrous material to form a thick stratum 67 with a beveled splicing stratum portion 68 in the space 66, which are deposited and accreted upon stratum 59 and stratum portion 64 and in space 66, and also integrated, united and infused with stratum 59, stratum portion 64, and the outer edge portion of stratum 65. The device may then be raised out of the bath and the blanking-off member 54^a removed. See Fig. 11. In this way the blank is composed of different materials in varying degrees of thicknesses, with a preponderance of pulp or like fibrous material in the conic or vibratile portion, and a preponderance of soft fibrous material in the border or supporting portion, all integrated, united, infused and knitted together to form an unitary integral blank. 130

The blank may then be removed, dried, and treated as above described.

135 By using blanking-off members with curled borders, to provide tapered spaces therebeneath, the integrating of the adjunctive conic and border strata or strata portions is effected with overlapping or splice-like effect thus enhancing the integrality of the fibrous unit and yet maintaining the pliability and suppleness of the border 140

and juncture portions of the unit whereby the vibratile or conic portion of the unit has unimpeded freedom of movement when vibrated to produce sound.

- 5 While I have herein described and upon the drawings shown a few illustrative embodiments of the invention and a few methods of producing the same, it is to be understood that the invention is not limited thereto but comprehends other 10 constructions, compositions, details, arrangements of parts, features, and process steps without departing from the spirit of the invention. Any number of strata of materials may be accreted and integrated in accordance with the 15 manner of this invention, without limit. As for example, the unit shown in Fig. 7 may have one or more thin strata of soft fibres and one or more thick strata of hard fibres in the conic portion, and one or more thick strata of soft fibres, and 20 one or more thin strata of hard fibres in the border portion of the unit. Likewise, the unit shown in Fig. 11 may have one or more thick strata of hard fibres, and one or more thin strata of soft fibres in the conic portion, and one or more 25 thin strata of hard fibres, and one or more thick strata of soft fibres in the border portion of the unit.

Having thus disclosed the invention,

I claim:

- 30 1. A vibratile sound producing member of diaphragmatic type comprising integrated strata of different fibrous materials.
2. A vibratile sound producing member of diaphragmatic type comprising integrated strata of alternate grades of fibrous materials.
3. A vibratile sound producing member of diaphragmatic type comprising integrated strata of plant fibrous material and animal fibrous material.
- 40 4. A vibratile sound producing member of diaphragmatic type comprising integrated strata of soft fibrous material and hard fibrous material.
5. A vibratile sound producing member of diaphragmatic type comprising integrated strata of pliable fibrous material and stiff fibrous material.
- 45 6. A vibratile sound producing member of diaphragmatic type comprising integrated strata of pulp fibres and textile fibres.
- 50 7. A sound producing diaphragmatic member, comprising a vibratile portion and a supporting portion, said vibratile portion being composed of integrated strata of different fibrous materials, and said supporting portion being pliable for affording free movement of said vibratile portion.
- 55 8. A sound producing diaphragmatic member, comprising a vibratile portion and a supporting portion, said vibratile portion being composed of integrated strata of soft and hard fibrous materials, and said supporting portion being pliable for affording free movement of said vibratile portion.
- 60 9. A sound producing diaphragmatic member, comprising a vibratile portion and a supporting portion, said vibratile portion being composed of integrated strata of soft and hard fibrous materials, the hard fibrous material predominating to give said vibratile portion stiffness for propagation of sound when vibrated, and said supporting portion being pliable for affording free movement of said vibratile portion.
- 70 10. A sound producing diaphragmatic member, comprising a vibratile portion and a supporting portion, said supporting portion being composed of soft and hard fibrous materials, the soft fibrous

material predominating to give said supporting portion suppleness for the free movement of said vibratile portion when vibrated, and said vibratile portion being stiff for propagation of sound.

11. A sound producing diaphragmatic member, comprising a vibratile portion and a supporting portion, said portions being composed of integrated strata of soft and hard fibrous materials of which the soft fibrous material predominates in the supporting portion to give it suppleness and the hard fibrous material predominates in the vibratile portion to give it stiffness, said portions being integrated at their juncture. 80

12. A sound producing diaphragmatic member comprising a vibratile portion and a supporting portion, said vibratile portion comprising a thick stratum of hard fibrous material and a thin stratum of soft fibrous material integrated with said thick stratum and being stiff for propagating sound when said vibratile portion is vibrated, said supporting portion comprising soft fibrous material integrated with said vibratile portion and being supple to afford freedom of movement of said vibratile portion when vibrated. 85

13. A sound producing diaphragmatic member comprising a vibratile portion and a supporting portion, said supporting portion comprising a thick stratum of soft fibrous material and a thin stratum of hard fibrous material integrated with said thick stratum and being supple to afford 90 freedom of movement of said vibratile portion when vibrated, said vibratile portion comprising hard fibrous material integrated with said supporting portion at their juncture and being stiff for propagating sound when said vibratile portion is vibrated. 100

14. A sound producing diaphragmatic member comprising a vibratile portion and a supporting portion, said vibratile portion comprising a thick stratum of hard fibrous material and a thin stratum of soft fibrous material integrated with said thick stratum and being stiff for propagating sound when said vibratile portion is vibrated, said supporting portion comprising a thick stratum of soft fibrous material and a thin stratum of hard fibrous material integrated with said thick stratum and being supple to afford 105 freedom of movement of said vibratile portion when vibrated, said vibratile and supporting portions being integrally united at their juncture. 110

15. In a process of making a fibrous sound producing member, the steps of accreting and integrating conjunctive strata of different kinds of fibrous materials, including the blanking-off of a portion while causing the accretion and integration of another portion. 115

16. In a process of making a fibrous sound producing member, the steps of accreting and integrating conjunctive strata of different kinds of fibrous materials on different portions of a porous former, including first accreting and integrating one portion while blanking-off another portion, and then accreting and integrating another portion while blanking-off the said one portion. 130

17. In a process of making a fibrous sound producing member, the steps of accreting and integrating adjunctive strata of soft and hard fibrous materials, and accreting and integrating therewith respectively and together adjunctive strata of hard and soft fibrous material, to form 140 an unitary stratified integral member. 145

18. In a process of making a fibrous sound producing member comprising a vibratile portion and a supporting portion, the steps of forming the vibratile portion with accreted and integrated 150

strata of different kinds of fibrous materials, forming the supporting portion with accreted and integrated strata of different kinds of fibrous materials, and integrating said portions at their juncture.

19. In a process of making a fibrous sound producing diaphragmatic member having a vibratile portion and a supporting portion, the steps of

accreting and integrating thin and thick strata of soft and hard fibrous materials respectively, accreting and integrating thick and thin strata of soft and hard fibrous materials respectively, and integrating and infusing said portions at the juncture thereof to form an unitary vari-stratified integral member.
